HOSIERY AND METHOD OF MAKING
THE SAMEJohn Harlin Baugh, Chattanooga, Tenn., assignor
to Hemphill Company, Central Falls, R. I., a
corporation of Massachusetts

Application December 16, 1931, Serial No. 581,346

23 Claims. (Cl. 66—172)

This invention relates to hosiery and methods of making the same, and wherein the hosiery is characterized by being weltless, i. e., single ply.

In the drawings:

Fig. 1 is a view showing a few wales and courses at the top of a stocking as the same is when it is removed from the knitting machine;

Fig. 2 is a similar view showing a few wales and courses of the finished stocking top, which latter is provided with a picot edge;

Fig. 3 is a view showing the unfinished stocking (Fig. 1) on a suitable form for shaping the same; and

Fig. 4 is a view similar to Fig. 3 showing the stocking still on the form, and showing said stocking after the pull thread has been removed thereby separating the stocking proper from a few waste courses.

Preferably although not necessarily each stocking is cast off the needles which thereafter commence the knitting of a few waste courses for the top of the next stocking by knitting on every other needle for one or more courses and on every needle for one or more courses and thereafter on every other needle. In Fig. 1, course 1 is shown as the last course knitted by all of the needles knitting a yarn 2; course 3, which is the immediately succeeding course, is shown as having been knitted with alternate needles the intermediate needles having cast off their stitches. The said alternate needles are shown in Fig. 1 as having knitted the wales 4, 5, 6, 7, etc., the intermediate stitches 8, 9, 10, etc. (course 1) being the stitches cast off by the intermediate needles as aforesaid. After the knitting of the course 3 any desired number of additional courses like course 3 may be knitted by the alternate needles until finally a loose course 11 is knitted by the said alternate needles only, the loops of

the loose course 11 being shown, Fig. 1, somewhat longer than they normally would be, for the purpose of clearly illustrating the invention. After the knitting of the course 11 the intermediate cylinder needles are restored to action, engaging the yarn in their hooks during the knitting of the first course 12 and then being maintained inactive during the knitting of the next few (three being shown) courses 12. Following the knitting of the courses 12 all of the needles preferably, though not necessarily, engage and knit a course 13 with a yarn 14, and draw the same through the loops, the alternate needles drawing loops of the yarn 14 through loops knitted with the yarn 2 during the knitting of the last course 12; while the intermediate

needles draw loops of the yarn 14 through loops drawn during the knitting of the first course 12, the loops or stitches drawn by the intermediate needles with the thread 2 being relatively elongated and constituting draw or tuck stitches 15. Following the knitting of the course 13 all of the needles continue to knit the leg of the stocking which stocking may thereafter be knitted in any convenient or desired manner.

Each stocking 16 after it has been knitted as hereinbefore described, is ordinarily dyed and then while in a more or less moist condition is placed on a suitable form 17 which is heated thereby causing the stocking to "set". According to the present invention, and preferably at this time, the strand of thread or yarn 2 which constitutes the pull course 11 is severed and removed in any suitable manner, the removal of the loose course 11 thus separating the stocking 16 from the waste portion 18 consisting of the courses 20 1 and 3.

Ordinarily when knitting single ply or weltless stocking tops, the first few courses thereof curl and it is not practicable to finish the same in such a way that the edges will be flat, i. e., will not curl. As shown at 19 in Figs. 3 and 4 the upper edge of the waste section 18 curls or rolls over the upper portion 18 and when the waste portion 18 is removed from the stocking 16 the resultant selvage, picot edge 20 has little or no tendency to curl, the stocking having been "set" by the heated form 17 prior to the severance of the waste portion 18 from the stocking proper. Thus the hereinbefore described method of knitting, namely, with a waste portion 18, in conjunction with the "setting" of the stitches by the heated form 17, provides a selvage and picot stocking top without a tendency to curl or at least with very little tendency to curl.

Fig. 2 shows the appearance of the picot edge 40 after removal of the loose course 11; or, in other words, shows how the edge or top of a stocking looks after it has been finished in a manner hereinbefore described. Inspection of Fig. 1 shows that the special stitches 15 extend across 45 four courses; whereas inspection of Fig. 2 shows the same tuck or draw stitches as extending across two knitted courses and into the picot edge of the fabric. This transformation is due to a cutting or removal of the pull course 11 which removes 50 support of the special stitches 15 which thereupon—due to the fact that the stocking is on the form 17 and that the tuck or draw stitches 15 tend to contract although not being so shown in Fig. 1—are drawn below the upper floats 21 which 55

floats finally assume the shape shown at 21', Fig. 2. The two strand portions of the thread or yarn 2 which constitute each tuck or draw stitch 15, finally assume the relative position shown in Fig. 2 being bound between the picot loop 21' and the floats 22 which were the intermediate floats, Fig. 1. The lowermost floats 23, Fig. 1, are likewise positioned in the completed fabric as shown in Fig. 2. The picot loops 21' remain in the position shown in Fig. 2, being inclined to tilt forward; the reason that such picot loops do not tend to straighten out being that the fabric is knitted circular and that there is an excess of yarn, i. e., more yarn than is measured by the circumference of the stocking at the top thereof.

The top shown in Fig. 2 provides a fast or selvage edge, the picot loops 21' being prevented from running by the special stitches 16 and the latter being prevented from running by being interlaced or interlocked with the picot edge loops 21' and the floats 22, 23, a strand of each tuck or draw stitch 15 passing between a picot loop 21' and a float 22 in the manner indicated in Fig. 2.

Preferably, although not necessarily, the product is a seamless stocking or half hose, i. e., one without a line of stitches uniting adjacent edges of a flat stocking blank.

In the foregoing description and in the appended claims, reference is made to special stitches, the limitation "special" being intended to include stitches knitted by the needles or some of them retaining loops or stitches in their hooks during the knitting of two or more courses, e. g. stitches commonly known as tuck or draw stitches. The limitation "special" is also intended to include other forms of stitches, especially when the special stitch construction assists in a selvage formation.

The present invention is not necessarily limited to the disclosed means for or method of beginning the knitting of the stockings, nor is it limited to the disclosed means for or method of forming the picot edge, although it is advantageous to knit the waste courses such as 3 upon alternate needles only; furthermore, there is no intention to limit the terms of the claims hereto appended other than by express limitations in the claims themselves.

The stocking hereinbefore disclosed is preferably knitted plain, i. e., on a knitting machine having a single bed of needles as distinguished from a rib machine.

This application is a continuation as to all common subject matter of application Ser. No. 539,503, filed May 23, 1931.

55 I claim:

1. A method of making a stocking consisting in knitting waste courses, knitting a selvage course or courses and other courses of the stocking, subjecting the stocking to finishing operations including placing the stocking on a suitable form, and separating the waste courses from the stocking proper, whereby undesired curling of the finished edge of the stocking is obviated.

2. A method of making a stocking consisting in knitting waste courses, knitting a selvage course or courses and other courses of the stocking, subjecting the stocking to finishing operations including placing the stocking on a suitable, heated form, and separating the waste courses from the stocking proper, whereby undesired curling of the finished edge of the stocking is obviated.

3. A method of making a stocking consisting in knitting waste courses, the last of which is a pull course, knitting a selvage course and other courses, transferring the knitted stocking to a

form and subjecting the said stocking to a finishing operation, and removing the pull course thus separating the waste courses from the stocking, whereby undesired curling of the stocking top is obviated.

4. In the manufacture of weltless hosiery, the steps of: knitting a stocking with its top made of a single layer, and with waste courses at the top of the stocking, boarding the stocking with the waste courses attached, and then removing such waste courses, whereby a stocking having a single layer at its top is produced and the stocking top is protected during the boarding of the stocking.

5. In the manufacture of weltless hosiery, the steps of: knitting fabric comprising a single layer, the fabric consisting of a plurality of distinctive portions including a stocking leg and waste portions at the top thereof, passing the stocking leg and waste courses through finishing steps, and then removing the waste courses, whereby a stocking having a single layer at its top is produced and which stocking is protected during the finishing steps by the waste courses.

6. A method of manufacturing a stocking consisting in knitting a plurality of courses some of which are waste courses and others of which constitute a finished stocking leg, thereafter finishing the stocking, the finishing including the removal of the waste courses subsequent to other finishing operations by which said other finishing operations undesired curling of the finished stocking top is avoided.

7. A method of manufacturing a stocking consisting in knitting a plurality of courses some of which constitute leg courses of a stocking and others waste courses, finishing the stocking, such finishing including placing the unfinished stocking on a heated form and, as a step in the finishing operations, removing the waste courses, whereby undesired curling of the finished stocking top is avoided.

8. A method of making a seamless stocking consisting in knitting a plurality of courses, some of which are adapted to be removed after the stocking has been subjected to finishing operations, and knitting other courses constituting the leg of the stocking, one or more of which courses constitutes a picot, selvage edge, finishing the stocking, the finishing including a step of separating the waste courses from the picot edge, such finishing avoiding undesired curling of the finished stocking.

9. An unfinished seamless stocking consisting of a plurality of courses some of which courses have the full complement of wales while other courses have alternate wales only, and one or more courses, between the courses having the full complement of wales and said other courses, constituting a selvage formation for the stocking top when said other courses are removed.

10. A plain or non-rib knitted stocking consisting of independent needle stitches, such stocking having a substantially non-curling, selvage top of single ply, the non-curling characteristic being the result of a finishing operation.

11. A plain or non-rib knitted stocking having a substantially non-curling, selvage top of single ply, the non-curling characteristic being the result of a finishing operation, some of the wales having special stitches at or adjacent to the top of the stocking.

12. A substantially non-curling, plain single ply, selvaged, plain knitted stocking top having selvage courses consisting of interspersed plain and special stitches.

13. A method of knitting a selvage fabric consisting in knitting waste courses on alternate needles only of a knitting machine and then causing all of the needles to take yarn and thereafter causing some at least of the needles other than the said alternate needles to knit special stitches while the remaining needles are knitting plain stitches. 5
14. A method of knitting a selvage fabric consisting in knitting one or more waste courses on alternate needles only of a knitting machine, the last such course being a pull course, and thereafter knitting the selvage fabric by knitting special stitches on alternate needles and knitting plain stitches on the intermediate needles. 10
15. A method of knitting a selvage fabric consisting in knitting on alternate needles only of a knitting machine for one or more courses, then causing all of the needles to take yarn, some at least of the needles other than the said alternate needles thereafter retaining yarn in their hooks during the knitting of one or more additional courses, and finally knitting on all of the needles. 15
16. In the manufacture of weltless hosiery, the steps of: knitting the stocking with its top made of a single layer, and with a ravel-off section attached to said top, boarding the stocking with the ravel-off section attached, and then removing the ravel-off section, whereby a stocking having a single layer at its top is produced and this stocking top is protected during the boarding operation. 20
17. A knitted stocking having at its upper end a fabric of single thickness with a picot edge, in combination with waste material above said edge knit integrally therewith having fewer wales in said upper end for drawing out a thread to part the waste material from the picot edge. 25
18. A knitted stocking having at its upper end a fabric of single thickness with a picot edge, in combination with waste material above said edge knit integrally therewith having drop stitches therein adjacent said picot edge for drawing out a thread to part the waste material from the picot edge. 30
19. A knitted fabric comprising a stocking having an upper edge of a single thickness and waste material knit integrally with said edge, said edge having a picot structure, and a plurality of courses of the waste material adjacent said picot having drop stitches therein, for the purpose of permitting separation of said material from said picot edge. 35
20. In a process of making a stocking, the steps of knitting waste material on a certain number of needles and bringing into action additional needles intercalated with the needles used in making said waste material and knitting on the increased number of needles a picot structure in the plain fabric and subsequently boarding the stocking and parting the waste material from the stocking by drawing a thread from said waste material. 40
21. A process of making a stocking, comprising the steps of knitting waste material having courses knit on all the needles and adjacent courses knit on a lesser number of needles, knitting the stocking with a picot edge adjacent said latter courses and subsequently boarding said stocking and parting the waste from the stocking by drawing a thread from one of the courses having a lesser number of wales. 45
22. A substantially non-curling, single ply, selvaged, plain knitted stocking top, having one or more selvage courses including special stitches. 50
23. A substantially non-curling, single ply, selvaged, plain knitted stocking top, having one or more selvage courses including special stitches, the selvage comprising a picot edge. 55

JOHN HARLIN BAUGH.
